UNITED STATES PATENT OFFICE.

CHARLES M. CULP, OF SOUTH BEND, INDIANA.

RAIL-SPLICER.

No. 901,524.

Specification of Letters Patent.

Patented Oct. 20, 1908.

Application filed October 2, 1907. Serial No. 395,643.

To all whom it may concern:

Be it known that I, CHARLES M. CULP, a citizen of the United States, residing at South Bend, in the county of St. Joseph and State of Indiana, have invented certain new and useful Improvements in Rail-Splices, of which the following is a specification.

This invention relates to rail joints or chairs.

One object of the invention is to provide means for effecting a permanent connection between abutting ends of rail sections and yet not interfere with contraction and expansion of the rails at their points of connection.

Another object of the invention resides in a new and novel means for mounting the splice bars of the joint and effecting a proper positioning thereof to insure a tight joint between the abutting ends of the rail sections.

With the above and other objects in view, the present invention consists in the combination and arrangement of parts hereinafter more fully described, illustrated in the accompanying drawings, and particularly pointed out in the appended claims, it being understood that changes may be made in the form, proportion, size and minor details without departing from the spirit or sacrificing any of the advantages of the invention.

In the drawings:—Figure 1 is a perspective view of my invention. Fig. 2 is a top plan view with a portion of the tread surface of the rails removed. Fig. 3 is a fragmentary elevation of abutting rail sections. Fig. 4 is a view illustrating a rail in section and my invention in elevation.

Referring now more particularly to the accompanying drawings, the reference characters 1 and 2 indicate abutting rail sections, each having a semi-circular transverse notch 3 in its web portion 4 for a purpose presently explained.

The character 5 indicates the base plate upon which the rail sections are mounted. This base plate is provided along one longitudinal edge with an inwardly directed lip 6 which overhangs the base flange of the rails and whose inner edge is undercut, as shown at 7, to overhang the beveled longitudinal edge 8 at the lower outer edge of the splice bar 9, while the opposite longitudinal edge of the base plate 5 extends considerably beyond the opposite side of the base flange of the rail sections and is turned upwardly upon a curve, as indicated at 10.

Coöperating with the splice bar 9 is a splice bar 11, whose lower edge is directed over the base flange of the rail sections and engages the upper surface of the base plate 5, as clearly shown in the drawings. Each splice bar 9 and 11 is provided with a perforation intermediate its ends for the reception of the bolt 12, which is held against displacement by means of the nut 13. This bolt and nut 12 and 13, respectively, holds the splice bars in coöperative relation and the bolt 12 is fitted in the semi-circular notches 3 of the meeting ends of the sections 1 and 2, whereby longitudinal contraction and expansion of the rail sections 1 and 2 is permitted without causing displacement of the splice bars. If the bolt 12 should be removed the splice bar 11 would be readily removable, if not liable to move by its own weight from its operative position, whereas the splice bar 9 would not be readily removable or accidentally movable unless the rail sections were moved by virtue of the beveled outer edge of the splice bar 9 lying under the undercut wall 7 of the lip 6 of the base plate 5. However, by forming the splice bar 9 separately from the base plate 5 instead of in one piece, as in my former patent No. 398,709, Feb. 26, 1889, I am enabled to shift the splice bar 9 longitudinally, if not laterally, out of coöperative relation with the base plate 5 and the rail sections, if desired. Moreover, I am enabled, by virtue of the peculiar connection between the splice bar 9 and the base plate 5 and the curved edge 10 of the latter, to obtain an efficient wedging action of both splice bars with respect to the rail section and yet not interfere with contraction and expansion of the section.

To insure the efficient wedging engagement of the splice bars with the rail sections, I provide a wedging plate 14, whose inner longitudinal edge is increased in thickness, as indicated at 14', for firm engagement with the splice bar 11, and whose outer edge is designed to engage the inner surface of the upwardly turned part 10 of the base plate 5. By forcing the outer edge of the tightening or wedging plate 14 down upon the curved inner face of the curved bar 10 of the base plate 5, the splice bar 11 is caused to slide into tight engagement with the web part of the sections 1 and 2 and incidentally insure a wedging of the splice bar 9 in engagement with the opposite sides of the web parts of

said sections by virtue of the wedging action had between the beveled and undercut faces 7 and 8, respectively. To cause this action of the wedging plate 14 it is simply necessary to manipulate the nut 15 upon the bolt 16, which latter passes through the wedging plate 14 and the base plate 5 at the base of its curved part 10, there being a boss 17 formed upon the under face of the base plate 5 at the base of its curved part 10, as clearly shown in Fig. 4. This boss provides for a firm engagement of the head 18 of the bolt 16. Other bolts 19 and 20 pass through the wedging plate 14 and base plate 5 and are provided with the nuts 21. These latter bolts and nuts may cooperate with the bolt 16 or they may be used for holding the inner edge of the wedging plate 14 tightly upon the splice bar 11, after manipulation 20 of the bolt 16.

Traffic over the rail sections is liable to cause more or less jarring and consequently loosening of the bolts, but to prevent loosening of the bolts, I provide means whereby 25 the nuts or bolts cannot turn. One form of means for this purpose resides in a locking plate having a head part 22 which engages the nuts 21, and a tail part 23 which engages the nut 13, there being a projecting lug 24 formed upon the head 22, which is provided 30 with a perforation to permit the passage therethrough of the bolt 16 and which is also provided with a yieldable lip 25 designed to be bent into engagement with one side of 35 the nut 15. Thus the bolt 16 holds the locking means against displacement and the latter in turn, by its peculiar formation and engagement with all of the nuts prevents accidental turning of the latter.

40 What is claimed is:—

1. The combination with abutting rail sections, of a base plate for the support of the rail sections, one edge of the base plate overhanging one side of the base flange of the rail sections and having an undercut-wall, the opposite edge of the base plate extending beyond the opposite edge of the base flange of the rail sections and being directed upwardly, a splice bar having a beveled edge for engagement with said undercut wall of the base flange, a second splice bar for engagement with the opposite sides of the rail sections, a wedging plate engaging the second mentioned splice bar and upwardly directed bar of the base flange, and means for securing the base plate and the wedging plate together.

2. The combination with abutting rail sections, of a base plate for the support of the rail sections, one edge of the base plate overhanging one side of the base flange of the rail sections and having an undercut-wall, the opposite edge of the base plate extending beyond the opposite edge of the base flange of the rail sections and being directed upwardly, a splice bar having a beveled edge for engagement

ment with said under-cut wall of the base flange, a second splice bar for engagement with the opposite sides of the rail sections, a bolt passed through the splice bars, a wedging plate engaging the second mentioned splice bar and upwardly directed bar of the base plate, and bolts passed through the wedging plate and the base plate to secure them together.

3. The combination with abutting rail sections, of a base plate for the support of the rail sections, one edge of the base plate overhanging one side of the base flange of the rail sections and having an under-cut wall, the opposite edge of the plate extending beyond the opposite edge of the base flange of the rail sections and being curved upwardly, a splice bar having a beveled edge for engagement with said under-cut wall of the base plate, a second splice bar for engagement with the opposite sides of the rail sections, a bolt passed through the splice bars, a wedging plate engaging the second mentioned splice bar and the upwardly directed part of the base plate, bolts passed through the wedging plate and the base plate, nuts upon all of the bolts, and locking means engaging all of the nuts to prevent accidental turning of the latter.

4. The combination with abutting rail sections, of a base plate for the support of the rail sections, one edge of the base plate overhanging one side of the base flange of the rail sections and having an under-cut wall, the opposite edge of the base plate extending beyond the opposite edge of the base flange of the rail sections and being curved upwardly, a splice bar having a beveled edge for engagement with said under-cut wall of the base plate, a second splice bar for engagement with the opposite sides of the rail sections, a bolt passed through the splice bars, a wedging plate engaging the second mentioned splice bar and the upwardly directed part of the base plate, bolts passed through the wedging plate and the base plate, nuts upon all of the bolts, a locking plate embracing one of said bolts and held upon the wedging plate by one of said nuts and having portions engaging all of the nuts to prevent accidental turning of the latter.

5. In a rail joint or chair, the combination with rail sections, of a base plate for the support of the rail sections, one edge of the base plate overhanging one edge of the base flange of the rail sections and having an under-cut wall, the opposite edge of the plate extending beyond the opposite edge of the base flange of the rail sections and being curved upwardly, a splice bar engaging one side of the rail sections and having a beveled edge for cooperative engagement with said under-cut wall, a splice bar engaging the opposite side of the rail sections, a bolt passed through the splice bars, the abutting ends of the rail sec-

tions each having a notch for registration with each other and through which said bolt passes to permit of contraction and expansion of the rail sections, a wedging plate engaging the second mentioned splice bar and the upwardly curved edge of the base plate for depression to wedge the splice bars tightly into coöperation with the rail sections, bolts passed through the base plate and 10 wedging plate to hold the latter in operative

position, nuts upon all of the bolts, and a locking plate having engagement with all of the nuts to prevent accidental turning of the latter.

In testimony whereof I affix my signature, 15
in presence of two witnesses.
